Fig. 1

Fig. 2

Fig. 3

Fig. 4

FIG. 1 is a top plan view of a drive housing and guides for gauge support carriage for press brake or the like showing my new design.

FIG. 2 is a right-hand side view of the unit with the front end up and the rear end down.

FIG. 3 is a rear elevational view thereof.

FIG. 4 is a front elevational view thereof.

The appearance of the left-hand side view would be a mirror image of the right-hand side view of FIG. 2.

I claim:

The ornamental design for a drive housing and guides for gauge support carriage for press brake or the like, as shown and described.
